UNITED STATES PATENT OFFICE.

PEARL N. JONES, OF PITTSBURGH, PENNSYLVANIA.

PASSENGER-CAR.

1,061,750.

Specification of Letters Patent.

Patented May 13, 1913.

Application filed July 20, 1911. Serial No. 639,538.

To all whom it may concern:

Be it known that I, PEARL N. JONES, of Pittsburgh, Allegheny county, Pennsylvania, have invented a new and useful Improvement in Passenger-Cars, of which the following is a full, clear, and exact description, reference being had to the accompanying drawings, forming part of this specification, in which—

10 Figure 1 is a sectional plan view of one form of passenger car embodying my invention the section being taken above the upper edges of the car doors; Fig. 2 is a side view of the same; Fig. 3 is an enlarged view 15 of one end portion of the car shown in Fig. 1; Fig. 4 is a sectional plan showing one of the rear steps and the rear doors on a larger scale the section being taken through the lower portion of one pair of the doors; and 20 Fig. 5 is a detail view illustrating one of the doors in its open position. Fig. 6 is a horizontal section taken through the upper portion of the doors, one pair of the doors being shown fully closed and the other pair 25 fully open; and Figs. 7 and 8 are detail sectional views, Fig. 7 being a section through the lower portion of one door in its closed position; and Fig. 8 being a section through the same door in its open position. Fig. 9 30 is a view similar to Fig. 2, but showing a modification.

My invention has relation to passenger cars, and more particularly to cars which are adapted for use on the streets of cities 35 and towns and commonly known as street railway cars.

The main object of my invention is to provide a car the platforms and floors of which can be reached from the street level 40 by a single step.

A further object of my invention is to provide a car of this character with a novel arrangement of the step and of the doors operating in connection therewith, whereby 45 the doors and step are entirely within the side lines of the car.

A still further object of my invention is to provide means whereby a door of increased width can be employed in connection 50 with the single step without interference with the floor or platform of the car.

The nature of my invention will be best understood by reference to the accompanying drawings, in which I have shown my 55 invention as applied to a motor-driven passenger car, and which will now be described, it being premised, however, that certain fea-

tures of my invention are also applicable to trailer cars, and that various changes may be made in the construction and arrangement of the several parts without departing from the spirit and scope of my invention as defined in the appended claims.

In these drawings, the numeral 2 designates the car floor, which is preferably continuous from one end of the car to the other, including the end platforms, and which is preferably entirely free from any internal cross-partitions or bulk heads.

3 designates the front end of the car, 4 the rear end, and 5 the sides.

The car may be provided with any suitable interior arrangement of seats 6.

In order to provide a car whose platform and floors can be reached by a single step, 75 I not only provide the feature of the continuous floor and platform level above described, but the car is also mounted upon specially low trucks. These trucks may be made specially low to bring the end portions 80 of the car floor nearer the ground, in different ways. In the form shown, I form these special low trucks by using wheels 7 of considerably smaller diameter than the standard wheels heretofore commonly used. I 85 also employ compact, relatively high-speed driving motors 8. By the use of such relatively small wheels and compact motors in the form shown, I am not only able to bring the floor and platforms much nearer the 90 street level than has heretofore been the practice, but I also decrease very largely the weight of the car and its equipment. The intermediate step portion is at a level one step above the ground and inside the side 95 lines of the car; and there is not over one step from the intermediate step portion to the car floor proper. By the use of special trucks (and by the words "special trucks" I mean any arrangement of the trucks in- 100 cluding its wheels which will bring the car floor sufficiently low), in connection with the lowering of the intermediate step portion to one step above the ground level, I bring the entering passengers within the car with 105 only one step, and thereafter there is not more than one step to the car floor itself.

In the particular car illustrated, I have shown two steps 9 and 10 at the rear end portion of the car at opposite sides, and two 110 steps 11 and 12 at the front end portion of the car and at opposite sides thereof. Ordinarily the steps 10 and 12 will not be used, and folding or removable seats 13 may be

provided over these steps. The step 9 is shown as of a sufficient length to provide for both entrance and exit doors, the entrance doors being marked 14 and the exit doors 15. The main exit, however, is at the front end 5 of the car by the step 11 and door 16. The doors 14 and 15 are preferably of the character and arrangement, and have operating mechanism 17 such as shown in my Patents 10 964,269 of July 12th, 1910, and 963,835 of August 2nd, 1910, although other approved door mechanism may be used. For a description of the actuating mechanism shown in Figs. 3 and 6, reference may be had to my 15 said patents. As will appear by reference to said patents, these doors extend downwardly below the car floor or platform to the outer edge portion of the step, and are arranged to have a combined swinging and 20 sliding movement in opening and closing, the doors assuming an edgewise position when opened substantially perpendicular to their closed positions, and whereby the doors in both opening and closed positions 25 are substantially always within the side lines of the car.

To provide the steps 9, 10, 11 and 12, the floor or platform is cut away to form pockets at the bottom of which the step is 30 located; and in order to properly support and carry these steps the side sills 18 of the car are depressed underneath the steps in the manner shown in Fig. 2. In this manner I am enabled to employ continuous side 35 sills, and at the same time provide a strong and secure construction and a step support which is evidently adapted to the single-step scheme of my invention.

In order to employ somewhat wider doors 40 than those shown in my patents above referred to, I cut away the one lower corner portion of each door, as shown at 19 in Figs. 2 and 4 and as also shown in Figs. 7 and 8, this cut-away portion being at the corner of 45 the door which is innermost when the door is in its open position. The cutaway portion is of the proper height so that when the door is opened it will, by reason of such cut-away portion, swing freely over the car floor 50 or platform, as shown in Fig. 5, a portion of the door overhanging the platform. In order that this cut-away portion may be normally closed, and thereby not afford any foot-hold when the doors are in closed positions, I provide the hinged flaps 20, which 55 normally close these cut-away portions, as shown in Figs. 2, 4 and 7. The hinges of these flaps are preferably provided with springs 21, so that as the door is opened 60 they are moved to closed position. When the doors are opened, the flaps assume the different positions shown in dotted lines in Fig. 7, until they finally lie back against the inner side of the door, as shown in full lines 65 in Fig. 8. Figs. 7 and 8 also show different

positions assumed by the doors in their combined swinging and sliding opening and closing movements.

The door 16 can be a sliding door, mounted to slide back into a pocket 22 in the side 70 wall of the car.

Instead of arranging the doors at the ends of the car as shown, they may be at the central portion of the car, as in my Patent No. 962,224 of June 21st, 1910. In this case the 75 central portion of the side sill of the car end framing will be bent downwardly underneath the central side step in the same manner as shown for the end steps in Fig. 2. This is shown in Fig. 9.

The advantages of providing a car which can be entered by a single step in the manner herein described, will be apparent. The cars can be loaded and unloaded very much more rapidly, which is an important feature 85 in modern street car traffic conditions. The single step when used is much more convenient, especially for women and children, and the provision of a motor-driven car having a single step and low trucks greatly decreases the weight of the car and its equipment. 90

By the word "continuous" in my claims, as applied to the floor, I mean to say that 95 there is no step in the length of this floor from one end to the other and not necessarily that all parts of the floor are at exactly the same level.

I claim:

1. A passenger car having a step and a 100 combined swinging and sliding door arranged to close over the outer edge of the step and to assume a position at substantially right angles to its closed position when opened, the door having a portion to overhang the car floor or platform when 105 opened; substantially as described.

2. A passenger car having its floor provided with a depressed portion or pocket, a 110 step therein, and a swinging and sliding door having a corner portion thereof cut away to clear the step; substantially as described.

3. A passenger car having its floor provided with a depressed portion or pocket, a 115 step therein, and a swinging and sliding door having a corner portion thereof cut away, together with means for covering the cut-away corner portion when the door is closed; substantially as described.

4. A passenger car having its floor provided with a depressed portion or pocket, a 120 step therein, and a swinging and sliding door having a corner portion thereof cut away, together with a spring-actuated flap 125 for covering the cut-away corner portion; substantially as described.

5. A passenger car having a step, and a 130 door inclosing said step when closed, the door being wider than the step and having

a corner portion cut away to permit it to move inwardly over the step when opened; substantially as described.

6. A passenger car having a step, and a door inclosing said step when closed, the door being wider than the step and having a corner portion cut away to permit it to move inwardly over the step when opened, together with means for closing said cut away portion when the door is closed; substantially as described.

7. A passenger car having an inclosed body extending from end to end of the car, special low swiveled trucks beneath the end portions of the car body and its floor, said car body extending beyond the trucks and having a side door opening leading directly into the car body, the body portion having a dropped frame portion extending below said opening, a door for closing said opening and a step portion within the car body at the door opening, the said low trucks and the drop portion of the frame coöperating to bring said step portion only one step above the level of the track and the car floor not more than the height of one step above said step portion; substantially as described.

8. A passenger car having an inclosed body extending from end to end of the car, special low swiveled trucks beneath the end portions of the car body and its floor, said car body extending beyond the trucks and having entrance and exit door openings side by side on the same side of the car and leading directly into the car body, the body portion having a dropped frame portion extending below said entrance and exit openings, and a step portion within the car body at said openings, the said low trucks and the drop portion of the frame coöperating to bring said step portion only one step above the level of the track and the car floor not more than the height of one step above the step portion; substantially as described.

9. A passenger car having an inclosed body extending from end to end of the car, special low swiveled trucks beneath the end portions of the car body and its floor, motors for said trucks, said car body extending beyond the trucks and having a side door opening leading directly into the car body, the body portion having a dropped frame portion extending below said opening, a door for closing said opening and a step portion within the car body at the door opening, the said low trucks and the drop portion of the frame coöperating to bring said step portion only one step above the level of the track and the car floor not more than the height of one step above said step portion; substantially as described.

10. A passenger car having an inclosed

body extending from end to end of the car, special low swiveled trucks beneath the end portions of the car body and its floor, said car body extending beyond the trucks and having a side door opening leading directly into the car body, the body portion having a dropped frame portion extending below said opening, a door for closing said opening, operating mechanism for said door having a distant control located in the entrance portion of the car, and a step portion within the car body at the door opening, the said low trucks and the drop portion of the frame coöperating to bring said step portion only one step above the level of the track and the car floor not more than the height of one step above said step portion; substantially as described.

11. A passenger car having an inclosed body extending from end to end of the car, special low swiveled trucks beneath the end portions of the car body and its floor, said car body extending beyond the trucks and having entrance and exit door openings side by side on the same side of the car and leading directly into the car body, a post between said openings, doors for said openings, operating mechanism for said doors, the body portion of the car having a dropped frame portion extending below the entrance and exit door openings and a step portion within the car body at the door openings, the said low trucks and the drop portion of the frame coöperating to bring said step only one step above the level of the track and the car floor not more than the height of one step above the step portion; substantially as described.

12. A passenger car having an inclosed body extending from end to end of the car, special low swiveled trucks beneath the end portions of the car body and its floor, said car body extending beyond the trucks and having entrance and exit door openings side by side on the same side of the car and leading directly into the car body, the body portion having a dropped frame portion extending below the said entrance and exit openings, and a step portion within the car body at said openings, the said low trucks and the drop portion of the frame coöperating to bring said step portion only one step above the level of the track and the portion of the car floor adjacent to the step portion not more than the height of one step above the step portion; substantially as described.

In testimony whereof, I have hereunto set my hand.
